UNITED STATES PATENT OFFICE.

WILLIAM H. M. BERTHON, OF LONDON, ENGLAND, ASSIGNOR TO BERTHON & CO., OF STREATHAM, ENGLAND.

COLLAPSIBLE MEAT SAFE OR COVER.

Application filed April 3, 1922. Serial No. 549,161.

To all whom it may concern:

Be it known that I, WILLIAM HENRY MILES BERTHON, a subject of the King of Great Britain, residing at 27 Elbourne Road, Tooting Bec, London, S. W. 17, England, have invented certain new and useful Improvements in Collapsible Meat Safes or Covers, of which the following is a specification.

This invention relates to collapsible meat safes and has for its object the provision of an inexpensive and effective meat safe or cover which is provided with a permanent or a detachable covering and may be readily collapsed thus occupying a very small space and be readily opened or expanded for use and will not present an unsightly appearance. To carry my present invention into practical effect I construct the meat safe or cover essentially after the following manner:

The foundation member consists of a metallic or other wire base ring of any convenient shape according to the size or shape of the joint or the like it is intended to cover, but such base ring is preferably elliptical in form.

Upon opposing sides of the said ring ear clips are securely fixed. The clip on one side of the ring, containing and forming the joint in the wire.

A plurality of ribs of metallic wire or other suitable substance are hinged to the ear clips, their shape being such that when folded down outwardly they conform to the shape of the base ring on their respective sides. The two central ribs are so pivoted in the ear clips that when the safe is opened or expanded for use they come into contact with each other and being each furnished with a slightly twisted loop, which loops engage and thus retain the ribs in such position, or I may employ any other convenient fastener or catch for such purpose.

The covering may be of any suitable net-like fabric or of a suitable ornamental fabric according to whether the safe is for employment in the larder or in the living-room.

The said covering is made in two sections, one section on each side of the central ribs, the coverings being sewn or fastened on their respective sides to the central ribs and also to the base ring. The covering is also fastened at suitable intervals to the other ribs so that when the safe is opened and the two

central ribs are connected as above described the covering assumes a dome-like form. When not in use the central ribs are disconnected and the ribs and their covering are folded down upon the base-ring on their respective sides. The base ring may be mounted upon a flat plain or ornamental stand so that the safe with its contents may be carried without opening the safe in which case, instead of lifting the safe to gain access to the contents the sides are let down which exposes the contents for use.

The meat safe in its expanded condition may be employed in the manner of an ordinary rigid wire meat cover.

In order that my said invention may be better understood and carried into practical effect I will now describe a preferred embodiment of same with the aid of the accompanying drawings throughout which like letters of reference denote like parts, and which drawings are to be deemed part of the specification and to be read therewith as descriptive and in no wise final.

Figure 1 is a longitudinal section of frame. Figure 2 is a plan of foundation ring. Figure 3 is an enlarged view of ear clip drawn to a larger scale, and Figure 4 is an end view of same.

The foundation member consists of a metallic or other wire base ring *a* which is elliptical in plan or of any other shape according to requirements.

Upon opposite sides of said base ring an ear clip *b* is fixed by soldering or other suitable means. The ends of the base ring terminate within the ear clips and are there secured in the manner indicated. The ear clips are formed from a circular shaped piece of metal folded or bent together so as to form a tube *b'* at the bottom for the reception of the base ring *a* and its ends, as shown drawn to a larger scale in Figures 3 and 4.

A plurality of metallic wire ribs *c* are hinged to the ear clip *b*, four being shown in the drawings, their shape being such that when folded down outwardly upon the base ring *a* on their respective sides they conform to the shape thereof. The bent ends of the ribs pass outwardly through the holes *d* in the ear clips.

The two central ribs *c* are pivoted in two merged holes *d* in order that when the safe is expanded for use they may be in con-

tact and are each furnished with a twisted loop *e* which loops engage and retain the said ribs in such position. These loops *e* may in some instances be added instead of being integrally formed by twisting the wire of the ribs, or I may employ any other convenient form of catch or fastener either integrally constructed with the ribs or otherwise.

- 10 A covering *h* of any suitable flexible net-like fabric or of a suitable ornamental material (according to the uses to which the safe is to be put) is fastened to the ribs, and to the foundation ring such covering being cut to sections and fastened to the ribs and foundation ring by sewing or otherwise. The drawing shows two such sections on each side of the safe attached to the ribs, and foundation plate, the covering sections 15 on one side being attached to one of the central ribs and the sections on the other side to the other central rib, so that when the safe is expanded for use and the two central ribs are in contact the covering assumes a dome-like form.

When the safe is not in use the central ribs are released from each other and the ribs and their covering are folded down upon the base ring on their respective sides.

The safe as above described may be mounted upon or detachably fixed to a suitable stand *f* by means of suitable clips *g* so that the contents may be carried without opening the safe, in which case, instead of lifting the collapsible portion of the safe to gain access 35 to the contents the sides are let down which exposes the contents for use.

The safe in the expanded condition without the stand may be employed in like manner to an ordinary rigid wire meat cover. 40

Claim.

A collapsible safe comprising a foundation ring, ear clips carried upon said foundation ring, a pair of collapsible members comprising a plurality of ribs pivoted to the 45 foundation ring, and a flexible fabric covering attached to said ribs and said ring, the ears on said ring having communicating apertures therein and a rib of each of said collapsible members pivoted in each of the 50 respective communicating apertures whereby the said ribs lie in contact when said collapsible members are in operative uncollapsed position.

In testimony whereof I have hereunto set 55 my hand.

WILLIAM H. M. BERTHON.
